UNITED STATES PATENT OFFICE.

PETER GRAHAM MACGREGOR, OF NEW YORK, N. Y.

DOUBLE-ACTING SYRINGE.

954,398.

Specification of Letters Patent.

Patented Apr. 5, 1910.

Application filed May 3, 1909. Serial No. 493,468.

To all whom it may concern:

Be it known that I, PETER GRAHAM MAC-GREGOR, of the borough of Manhattan, city and State of New York, have invented a certain new and useful Improvement in Double-Acting Syringes, of which the following is a specification.

This invention pertains to a type of the foregoing devices in which a stream of liquid is adapted to be ejected from the syringe at each inward and outward movement of a piston or plunger.

The invention relates particularly to means whereby the suction inlet from the tank or liquid reservoir is taken from the lowermost part thereof whatever the discharging position of the syringe whether it be inclined upward or downward, or is held horizontally, it being immaterial also what the angular position with reference to the axis of the discharge orifice may be.

Certain other features of the invention relate to the control of the ports leading from the respective spaces on opposite sides of the piston to the space in direct communication with the discharge orifice. These various features together with novel details of construction are illustrated in the accompanying drawing, in which—

Figure 1 is a longitudinal section through a syringe embodying the features of my improvements. Fig. 2 is a similar section upon a somewhat larger scale, parts being broken away. Fig. 3 is partly a longitudinal section; partly an elevation showing among other things the gravity positioned double ported suction inlet. Fig. 4 is a perspective detail of the locking device for locking the piston rod to and thereby hermetically sealing the reservoir when the syringe is not in use. Fig. 5 is a modified construction of the suction inlet.

Similar characters of reference designate corresponding parts in all figures.

The present double acting syringe may be used for various purposes among which is that of a portable fire extinguisher.

It comprises a suitable tank or reservoir provided with a suitable filling plug *a* and here embodying a cylindrical body portion *2* having hemispherical ends *2', 2''*. To one of these ends a nozzle *3* is secured while the opposite end is provided with a stuffing box *4* for a piston rod *5*.

An object of the present invention is to provide an organization such that when the

instrument is suspended nozzle downward from a support (as for instance when not in use) the pressure due to the weight of liquid in the syringe shall not operate to cause leakage past valve-mechanism leading to the discharge nozzle. I have therefore secured to nozzle *3* a discharge tube *6*, the bore of this tube being a continuation of the discharge outlet in nozzle *3* and the free or entrance end to the tube being contiguous to the stuffing box end of the reservoir. Tube *6* is located in piston rod *5* which is made hollow for the purpose and for the further purpose of permitting the controlled flow of the liquid from end to end of the piston rod and out through tube *6*. The piston rod works in a cylinder *7* entrance of the liquid to either end of which, that is to the cylinder space on either side of the piston therein, may take place from either end of the reservoir, the suction furthermore being independent of the position angularly of the cylinder axis in which the reservoir may be held. These various results are here attained by the provision of a multiple ported suction inlet (hereinafter termed double ported) and by journaling cylinder *7* to tube *6* adjacent to nozzle *3* and to piston rod *5* adjacent to stuffing box *4*.

In the form illustrated in Figs. 1, 2 and 3, the double ported inlet comprises two similar fittings *8*, each comprising a head *8'* secured to the corresponding end of cylinder *7* and by means of which heads the cylinder *7* is rotatably mounted on tube *6* and rod *5* as aforesaid. Each fitting *8* also comprises a tubular part *8''* the bore of which is open to the cylinder space at that end, see port *8''* and constitutes a valve chamber for a valve *9* which controls the passage through port *9'* in a part *10* of the fitting which preferably is angularly related as indicated. Part *10* also contains a valve chamber for an inwardly opening and outwardly closing valve *11* co-operative with a seat in a cap *11'* on the part. Fittings *8, 8* are rigidly joined together by tubular rod *12* the bore of which communicates at each end by a corresponding port *12'* with port *9'* at that end. It is contemplated that the weight of fittings *8, 8* and tubular rod *12* shall be sufficient to cause the parts to freely rotate about the axis of the piston rod so that the suction inlets controlled by valves *11, 11*, shall be substantially vertically beneath the piston axis whatever the rotarial position of the

reservoir. It is also evident that the described disposition of ports and tubular rod 12 permits the liquid to be drawn from either end of the reservoir, thus making it immaterial whether the reservoir is full or partially empty or held horizontal at the time of discharge, or inclined upward or downward.

Instead of the ball valves 11, 11, described, 10 their function may be performed by disk valves 11², 11², connected by a rod 11³ in rod 12 and mounted in corresponding valve chests 11⁴, 11⁴ rigid with the respective tubular parts 8², 8².

15 The piston mounted on rod 5 is a two part one comprising a part 13 rigid with said rod and suitably packed, see 13', and a part 14 slidable on the rod between limits defined by part 13 and a shoulder-forming closure 20 15 at the end of rod 5. Packing 14' of piston part 14 fits sufficiently tight against the bore of cylinder 7 to cause during the initial movement of the piston in either direction the relative shifting of the piston part from 25 one extremity to the other extremity of its limited movement; the piston part thereafter is carried along by the piston rod during its further motion.

At one extremity of its movement part 14 30 shuts off passage through ports 15' (one or more) passing through the wall of the piston rod. At the other extremity of its movement these ports are opened while other ports 16 (one or more) at the opposite 35 side of the movable piston part are closed, these latter ports being open when the piston part is in the first mentioned position. When ports 16 are open, corresponding to a withdrawal of the piston rod, the liquid in 40 front of the advancing piston passes through openings 17 in piston part 13, ports 16, hollow piston rod 5, and thence into tube 6 from whence it can pass outward through the nozzle. The passage taken by the liquid 45 when the motion is reversed, via ports 15 will be readily understood from what has been described.

Air may enter the reservoir through stuffing box 4 to take the place of the ejected 50 liquid since the packing in the box may be made sufficiently porous to permit this.

It being contemplated that the instrument shall be capable of being hung up by its handle when not in use means are provided 55 for locking piston rod 5 to the reservoir when this rod is at the inner end of its reciprocatory movement. This locking action is also here utilized to hermetically seal the reservoir at its packing box end thus preventing evaporation through the more or 60 less porous packing therein. That is to say, when piston rod 5 is thrust inward by means of its hand piece 18 and given an axial turn of its hand piece 18 and given an axial turn 65 hooks 19', 19' on a fixture 19 secured to the rod are adapted to engage with respective

retaining catches 20, 20 provided on the stuffing box cover 21. This locking motion also serves to draw packing material 22 on the underside of fixture 19 firmly against cover 21 and thus shut off communication 70 between the interior and exterior through the packing in the stuffing box. Preferably also, hollow piston rod 5 is provided internally with a valve 23 adapted to close the open end of tube 6 when the rod is locked 75 to the reservoir and thus prevent evaporation through the syringe nozzle.

Having described my invention, I claim,

1. In a syringe the combination with a piston, piston rod and cylinder, of a reservoir and a suction inlet journaled to freely 80 rotate about an axis in line with the piston rod axis.

2. In a syringe, the combination of a reservoir having a discharge orifice at one end, 85 a cylinder in the reservoir, a piston, a piston rod projecting from the opposite end of the reservoir, and a double ported suction inlet journaled adjacent to each end of the reservoir to freely rotate about an axis in line 90 with the piston rod axis and whose ports are contiguous to the opposite ends of the cylinder and communicate with each other whereby liquid may be discharged from the reservoir in various positions thereof as specified. 95

3. In a syringe the combination of a reservoir, a cylinder therein, a piston, a hollow piston rod projecting from one end of the reservoir, a discharge nozzle fixed to the opposite end of the reservoir, a tube in said 100 piston rod which is secured to and constitutes a continuation of the nozzle orifice, said piston being adapted to slide along said tube, and valve mechanism for controlling the entrance of liquid to and its discharge 105 from the cylinder space on opposite sides of said piston.

4. In a syringe, the combination of a cylinder, a reservoir, a discharge nozzle secured to one end, a hollow piston rod extending 110 from the opposite end of the reservoir and provided with ports for the discharge from opposite ends of the cylinder, a tube secured to said nozzle and projecting through said hollow piston rod to a point adjacent to the 115 opposite end of the reservoir, a solid piston part secured to said rod, and a shiftable piston part mounted on said rod and adapted to be frictionally held in a stationary position during the initial movement of the rod 120 in either direction and to thereby alternately open and close said ports during the reciprocation of the rod.

5. In a syringe, the combination of a reservoir provided with a discharge nozzle, a 125 piston, a hollow piston rod, a tube in said rod forming a continuation of said discharge nozzle, a valve carried by said piston rod and adapted to close the opening through said tube, a stuffing box on the reservoir 130

through which said rod works, a locking fixture on said rod, a locking part on said reservoir, and packing carried by said rod for sealing the stuffing box when said locking fixture and locking part coöperate to close said valve.

In witness whereof I have signed this

specification in the presence of two subscribing witnesses.

PETER GRAHAM MacGREGOR.
